UNITED STATES PATENT OFFICE

HENRY O. COSTELLO, OF PROVIDENCE, RHODE ISLAND

GAME APPLIANCE

Application filed September 30, 1930. Serial No. 485,454.

This invention relates to an improved game appliance in the form of a golf club which may be more specifically defined as a golf club adapted for use for practice, although it may be employed not only in practicing swings to enable the player to develop accuracy in striking the ball but it may be employed also as a means for obtaining exercise and recreation apart from its value as an adjunct to the playing of golf in that it may be used either by an individual or by several players to test their skill in hitting an object, such as a golf ball, so as to cause the ball to be trapped by the club.

One object of the present invention is to provide a golf club having a transverse opening formed in the head or having the interior portion of the head cut away to leave a peripheral rim corresponding in outline substantially with the shape of the head of one of the clubs used in playing golf but provided with an opening extending through the head inwardly of said rim of sufficient size to permit the passage of a golf ball therethrough, whereby when the club is used for hitting a ball the ball will pass through the opening in the club head whenever the swing of the club is made in such a manner that it would meet the ball fairly if the club were of the regulation type.

Another object of the invention is the provision of a ball retaining or trapping means carried by the club head in such a manner as not to interfere with the free movement of the club or its use in striking a golf ball, but so positioned and held relative to the club head as to positively trap and retain a golf ball fairly struck by the club head.

Other objects and advantages of the invention relate to various improved details of construction and novel arrangements of the parts as will be more fully set forth in the detailed description to follow.

Referring to the drawing:—

Fig. 1 is a perspective view of the improved game appliance illustrating the position of the same with relation to a golf ball and showing the location of the parts as the ball is about to be struck by the club,

Fig. 2 is a front elevational view of the head of the club looking towards that side which is nearest to the ball as the club is swung in trapping the ball, and,

Fig. 3 is a vertical sectional view through the head of the club and the ball retaining means, and an elevational view of the ball, showing the position of the parts in addressing the ball.

In the embodiment of the invention illustrated herewith 1 designates generally the improved club which is provided with a shaft 2 having one end thereof wound with tape as at 4, to provide a hand grip, and the opposite end secured in a boss 5 carried by the club head 6.

The club head 6 comprises a rim 7 which may be of integral construction and which may correspond substantially in its external form with the shape of the head of a club commonly used in playing golf. That portion of the club head which is located inwardly of the rim 7 in the usual golf club head is cut away to form an opening 8 extending through the head, which opening is preferably of sufficient size to permit the free passage of a golf ball 9 therethrough when the club is swung in such a manner as to meet the ball fairly with that portion of the head 6 which would be the striking surface of the ordinary golf club head. The opening 8 formed in the head 6 may be of any desired shape but I preferably make it to conform roughly with the general contour of the club head and thus form the rim 7 of substantially uniform radial extent throughout the major portion of its length.

A ball retaining or trapping member 10 is secured to the rim 7 of the club head for trapping or retaining a ball after it has passed through the opening 8 in the club head, and this ball retaining or trapping member may be formed from leather, fabric or the like and shaped to form an open ended bag, or may be of mesh construction as shown herein and formed from leather, fabric or metal strips suitably connected together or interwoven to provide a mesh-work adequate to receive and retain a ball which has passed through the opening 8 in the club head.

In the embodiment of the invention shown herein that portion of the rim 7 which is adapted to pass beneath the ball 9 as the ball is struck is beveled slightly as indicated at 12 to facilitate the passage of the ball through the opening 8.

In the present form of the invention, also, the ball trapping or ball retaining member 10 is secured to the rim 7 by forming an internal ledge 14 upon that side of the rim 7 which is at the left as seen in Fig. 3, and securing thereto a strip 15, in any suitable manner as by rivets 16. The semi-elliptical strands 17 forming the ball retaining member have their ends secured to or are formed integral with the strip 15, and the circular or elliptical strands 18 extending transversely of the bag-like member 10 and secured to the strands 17 at the points where they cross as by rivets or other suitable fastening means 19.

It is obvious that the ball retaining member 10 may be made in various ways and may be secured to the rim 7 by a variety of means. For example, the member 10 may be made of continuous sheet material, such as leather, fabric or the like, or may be formed from any suitable metal, fabric, leather, raw hide or other strands interwoven together or secured to each other at their crossing points by being knotted together or otherwise attached. The manner of attaching the ball trapping member 10 to the rim 7 may also be accomplished in a variety of ways, such, for example, as by forming an external ledge or flange upon the rim 7 instead of the internal ledge 14 as shown, or by forming a groove in the edge of the rim 7 for receiving portions of the member 10, or by providing radial openings in the rim 7 for the insertion of the ends of certain of the strands forming the member 10 or lacing means for securing the member 10 to the rim.

Since I am aware that various changes may be made in the form and arrangement of certain of the parts, a few of which have been enumerated for the purpose of illustration, it is to be understood that my invention is not to be limited in its broader aspects to the precise arrangement of the several parts as shown and described, but that the particular form and arrangement of the parts as shown are for the purpose of illustration and that the appended claims are to be broadly construed in the light of my disclosure.

55 What I claim is:—

1. An improved golf club for use in practice comprising a head shaped to conform in outline with the shape of a golf club head and having an opening therein extending transversely of the head, the opening being of sufficient size to permit the passage of a golf ball therethrough.

2. A practice golf club having a skeleton head the outline of which is shaped to conform substantially with the shape of a golf

club head and having the central portion of the head cut away to provide a transverse opening through the head in the direction of movement of the club head when swung to strike a golf ball, and means for retaining the ball in proximity to the head after it has passed through the opening in the club head.

3. An improved game appliance comprising a shaft portion, a head portion of skeleton shape the exterior surface of which conforms substantially with that of the head of a golf club but having the interior thereof cut away to provide a transverse opening through the head of the club of sufficient size to permit the passage of a golf ball therethrough, and a bag-like member, the open end of which is secured to the said skeleton head upon the side thereof opposite to the direction of movement of said head when employed in trapping a golf ball.

4. A game appliance comprising a shaft, a skeleton head having a portion for attachment to said shaft and provided with a transverse opening extending therethrough, and a ball retaining member provided with an open end, the open end of said ball retaining member being secured to said head in such a manner that the open end thereof coincides substantially with the opening in said head.

5. A golf club for use in practice, comprising a shaft, a club head secured to said shaft and comprising a skeleton portion one side face of which is located substantially in a common plane corresponding to the striking face of an ordinary golf club and which is provided with a transverse opening extending through the golf club head of sufficient size to admit a golf ball.

6. A practice golf club comprising a shaft, a head secured to the shaft and provided with an unobstructed opening extending transversely therethrough and in a direction at substantially right angles to said shaft, and means secured to one side of said club head for retaining a golf ball passed through the transverse opening.

7. A practice golf club comprising a shaft, a head provided with an angular portion for attachment to said shaft, said head being in the form of an elongated loop one side of which is substantially straight throughout the major portion of its extent, the angular portion of said head extending outwardly from one of the shorter sides of said loop and in a direction away from the straight side of the elongated loop.

In testimony whereof I have affixed my signature.

HENRY O. COSTELLO. 125
